UNITED STATES PATENT OFFICE.

ALEXANDER C. RINDSKOPF, OF CHICAGO, ILLINOIS, ASSIGNOR TO NORTH AMERICAN WATCH COMPANY, A CORPORATION OF OHIO.

DESIGN FOR A WATCHCASE.

Application filed July 7, 1924. Serial No. 10,074. Term of patent 7 years.

To all whom it may concern:

Be it known that I, ALEXANDER C. RINDSKOPF, a citizen of the United States, residing at Chicago, in the county of Cook and State of Illinois, have invented a new, original, and ornamental Design for Watchcases, of which the following is a specification, reference being had to the accompanying drawing, forming part thereof, in which—

Fig. 1 is a front elevation of a watch case.

Fig. 2 is a side view thereof.

I claim:

The ornamental design for a watchcase, as shown.

In witness whereof I have affixed my signature.

A. C. RINDSKOPF.
